TORQUE CONVERTER FOR MIXING DRUMS

Richard J. Kacena, Chicago, Ill.

Application December 21, 1951, Serial No. 262,860

4 Claims. (Cl. 259—85)

1

This invention relates in general to a mixing drum which is rotatable about a horizontal axis from one position to another, such as from a load-receiving position wherein a door-equipped lateral opening is relatively high to a second position wherein the load is free for gravity discharge therefrom. Such a drum is cylindrical in form, with heads at opposite ends extending in parallel planes that are substantially vertical.

With a drum of this character there is provided a power-driven shaft extending axially thereof and beyond its opposite ends to be rotatably supported in suitable bearings. This shaft carries a suitable stirring means to be advanced through the load of loose material and may take the form of a plurality of fixedly connected radial arms supporting a blade (or blades) which is extended lengthwise of the drum close to the inner face of its curved wall. In operation, the loose material within the drum is stirred, tumbled, displaced, and mixed by the advancing movement of the blade within the drum. At the conclusion of the mixing operation, it is usual to rotate the drum through the necessary distance for shifting its lateral opening to discharge position. The load is then free to fall out by gravity, assuming that the door is opened for this purpose.

No special problem is involved in providing for movement of the stirring means within the drum. However, when the loaded drum itself is to be turned to discharge position, it has not been possible heretofore to convert satisfactorily any of the torque developed from power operation of the stirring means to effective use in a controlled rotation of the drum itself. At present, in most of the mixing drums used in many industries, this rotation of the drum is performed by hand, and where heavy loads are involved this operation requires considerable effort on the part of the attendants.

It is a primary purpose of this invention to provide for mixing drums of the character described a torque convertor whereby the power employed for operation of the stirring means within the drum may also be utilized to establish a state of equilibrium therefor whereby, with a minimum of effort, the drum may be rotated, either direction, to or from any desired position, such, for example, as a dumping position where the lateral opening into the drum is disposed at a relatively low down point. The means for accomplishing this objective, as hereinafter disclosed in detail, are simple and inexpensive to produce and operate, and may be relied upon to

2

facilitate and expedite the successive load treating operations for which the drum is designed.

A suggestive embodiment of this invention is illustrated in the accompanying drawing wherein:

Figure 1 is a longitudinal vertical section taken centrally through a conventional mixing drum equipped with my improved torque convertor mechanism;

10 Fig. 2 is a semi-diagrammatic view in transverse section through the drum as it appears when rotated to the position wherein its lateral opening is up, and Fig. 3 which is a similar view shows the drum rotated to a position wherein its lateral opening is down; and

15 Fig. 4 is a vertical section, taken on line 4—4 of Fig. 1.

As herein shown, a pair of spaced stands A up-stand from a base B to support between them a horizontal shaft C which extends axially through a cylindrical drum D having closure heads 10 and 11 at its opposite ends. A rotatable mounting for the drum is provided by a bushing 15 rotatably fitted over one end portion of the shaft and carried within a bearing 16 that is rotatably supported in a collar 17 having radially extended arms 18 that are connected by bolts 19 (or otherwise) to the drum head 10, and by a bushing 20 rotatably fitted upon the opposite end portion of the shaft and rotatably supported within a collar 21 equipped with arms 23 that are extended outwardly for connection, as with bolts 24, to the drum head 11. The collar 21 is itself journaled for rotation in a two-part bearing 25 that is carried at the upper end of the proximate stand A.

20 The outer end of the collar carries a transversely disposed mounting plate 32 to which is affixed a housing E, and constituting therewith and with the drum D a unit that is mounted to swing about the axis of the shaft C. In the mounting plate and opposite wall 33 of the housing are journaled for rotation the opposite ends of an idler shaft 35 upon which is fixedly carried a pinion 36 and a gear 37. This idler shaft is disposed with its axis eccentrically of the axis of the shaft C. The pinion 36 meshes with a gear 38 that is carried fast on the shaft C at a point close to its end, and the gear 37 is in mesh 25 with a pinion 40 formed on a relatively high power-input shaft 41 one end of which is journaled in the housing wall 33 and extended therethrough to carry fast on its outer end portion a sprocket wheel 42. The opposite end of the in- 30 put shaft 41 is journaled to rotate freely within

an axial socket 43 in the end of the shaft C and in the same direction therewith. The axis of the input shaft 41 is concentric with that of the drum shaft C. An endless chain 45 runs over the sprocket wheel 42 and also over a similar wheel 46 on the shaft of a motor F that is mounted on the base B. When operated, power from the motor will be transmitted through the gear train to rotate the shaft C, the housing and transmission, together with the drum to which the housing is fixedly secured, tending to remain stationary therewith. Due to the preponderance of the housing weight being located well below the two coaxial shafts C and 41 (as viewed in Fig. 1), it may be desirable to position a weight 47 at the housing top to serve as a counterbalance therefor.

Fitted upon the shaft C within the drum at opposite ends thereof is a pair of cellars 50 equipped with sealing gaskets, and therebetween is carried a stirring means adapted to be moved through the loose material in response to rotation of the shaft. As shown, this means comprises a pair of spaced arms 51 that are carried fast by the shaft and extended radially therefrom to support between them a blade 52 which is disposed longitudinally of the drum at a point close to the inner face of its curved wall. A further blade 53 may optionally be carried inwardly of the blade 52 to be supported therefrom by an arm 54. With each operation of the shaft C, the blade (or blades) is moved through a circular path within the drum to stir, displace, or mix the loose material therein that is to be treated. A lateral opening 57 is provided in the curved wall of the drum and equipped, if desired, with a door 58 having a suitable latch whereby to provide a closure therefor. When in the position of Fig. 2, the drum will receive and retain its load of loose material to be operated upon by the stirring means, but when the drum is turned to the position of Fig. 3 (or further), its contents will be gravity-discharged through the opening 57.

The material in the drum, when acted upon by the stirring means, offers a resistance that is approximately equal to the friction obtaining between the material and the inner surface of the drum. A torsional force is thereby exerted on the drum substantially the same as the force that is generated by the resistance of the loose material to the movement of the stirring means therethrough. These two forces are also exerted in the same direction. Since the drum D and housing E are fixedly interconnected, this same torsional force is transmitted back to the housing as well, but in a direction opposite to the frictional torque that is transmitted to the housing through the idler shaft 35. A condition of substantial equilibrium is thereby achieved, and the net result is to neutralize the resistance of the material in the drum to turning movement of the latter. The drum may accordingly be manually rotated, or otherwise, with a minimum of effort, in either direction, and through one or more revolutions. This balancing of forces continues irrespective of the amount of frictional torque generated in the drum, due to the resistance offered by the loose material therein to movement of the stirring means therethrough. Any variation in such resistance (due to different densities, consistencies, volume, etc. in the material) is accompanied by a corresponding change in the amount of torque whose value is approximately equal thereto and opposite in its direction.

The maintenance of a balanced condition in the forces present will for all practical purposes reduce to the zero point the effort involved in manually rotating the drum. However, in some cases it may be desirable to utilize a light auxiliary power means for this purpose. Such an arrangement is suggested in Fig. 1 where a sprocket wheel 60 is mounted fast on the collar 17, to be engaged by an endless chain 61 which is trained over a sprocket wheel 62 that is mounted free on the shaft 63 of an auxiliary motor G. A collar 64 that is splined on the shaft of this motor is shiftable in response to operation of a control lever 65 so as to engage or disengage the proximate end of the sprocket wheel 62. As by means of coacting clutch teeth on the collar 64 and sprocket wheel 62, power from the motor G is transmitted to the collar 17 thereby to revolve the drum whenever the control lever 65 is operated to the proper position for this purpose. Due to the state of equilibrium that is maintained by the means already described, the power required for rotation of the drum to and from any desired position need be but very small—perhaps one per cent of that of the motor F which operates the stirring means within the drum.

A mixing drum equipped with the present torque converter may be used to advantage in various industries for operation upon different materials. In the construction industry, for example, this would include mixers for concrete, plaster and the like. Manifestly the effort involved in rotating a normally stationary loaded drum from one rotative position to another, either way and any distance, is reduced to a minimum when the torque converter of this invention is applied thereto.

I claim:

1. A torque converter mechanism of the kind described in which is combined a cylindrical drum having a horizontal axis and provided in one wall thereof with an opening through which loose material may pass into and out of the drum, an axial mounting at one end of the drum for rotatable support thereof, a collar fixedly secured to the opposite drum end, axially thereof, and extended outwardly therefrom, a shaft extending axially through the drum and through the collar for rotatable support thereof, a bearing wherein the collar is rotatably supported, a housing fixedly secured to the outer end of the collar, a transmission within the housing comprising a power-input shaft coaxial with the drum shaft, an idler shaft mounted in said housing for bodily movement therewith and having its axis eccentrically of the drum shaft axis, intermeshing gears and pinions carried by the input and idler shafts and by the drum shaft to establish a train of driving connections therebetween, arms fixedly carried by the drum shaft and extending laterally therefrom, and a blade supported by the arms and disposed lengthwise of the drum relatively close to the inner surface of its curved wall, the arrangement being such that the frictional torque on the drum, occasioned by resistance of the loose material therewithin to movement of the blade therethrough, will be transmitted back to the housing in an amount approximately equal to that transmitted to the housing by the idler shaft, but in the opposite direction, thereby to produce substantially a condition of equilibrium permitting rotation of the drum in either direction through 360° or more with a minimum of effort.
2. A torque convertor mechanism of the kind

described in which is combined a cylindrical drum having a horizontal axis and provided in one wall thereof with an opening through which loose material may pass into and out of the drum, an axial mounting at one end of the drum for rotatable support thereof, a collar fixedly secured to the opposite drum end, axially thereof, and extended outwardly therefrom, a shaft extended axially through the drum and collar for rotatable support thereof, a bearing wherein the collar is rotatably supported, a housing at the outer end of the collar and fixedly mounted to rotate with the drum, a transmission within the housing comprising a power-input shaft coaxial with the drum shaft, an idler shaft mounted in said housing for bodily movement therewith and having its axis eccentrically of the drum shaft axis, intermeshing gears and pinions carried by the input and idler shafts and by the drum shaft to establish a train of driving connections therebetween, and stirring means fixedly carried by the drum shaft and extending away therefrom into engagement with loose material contained within the drum to be advanced therethrough when the shaft is rotated relative to the drum, the arrangement being such that the frictional torque on the drum, occasioned by resistance of the loose material therewithin to movement of the stirring means therethrough, will be transmitted back to the housing in an amount approximately equal to that transmitted to the housing by the idler shaft, but in the opposite direction, thereby to produce substantially a condition of equilibrium permitting rotation of the drum in either direction through 360° or more with a minimum of effort.

3. A torque convertor mechanism of the kind described in which is combined a cylindrical drum having a horizontal axis and provided in one wall thereof with an opening through which loose material may pass into and out of the drum, axial mountings at opposite ends of the drum for rotatable support thereof, a shaft extending axially through the drum and rotatable relative thereto, a motor, a transmission fixedly carried at one end of the drum in substantially balanced relation axially thereof and comprising two shafts, one having its axis concentric with the axis of the drum shaft and the other eccentric thereof, driving connections between (1) the concentric and eccentric shafts in the transmission, (2) the eccentric shaft and the drum, and (3) the concentric shaft and the motor, whereby to transmit

power from the motor to the drum shaft for operation thereof, and stirring means carried by the drum shaft and extending away therefrom into engagement with the loose material contained within the drum to be advanced therethrough when the shaft is rotated relative to the drum, the arrangement being such that the frictional torque on the drum, occasioned by resistance of the loose material therewithin to movement of the stirring means therethrough, will be transmitted back to the housing in an amount approximately equal to that transmitted to the housing by the eccentric shaft, but in the opposite direction, thereby to produce substantially a condition of equilibrium permitting rotation of the drum in either direction through 360° or more with a minimum of effort.

4. Apparatus for mixing and agitating materials comprising, a mixing drum mounted for rotational movement to enable loading and unloading thereof through an opening therein, a rotatable blade-mounting shaft mounted coaxially with the drum for movement with respect to the drum, a blade secured to said shaft for agitating material in said drum and creating, through the agitated material, a force which tends to rotate the drum, a power source for rotating said blade-mounting shaft, and mechanism for utilizing the torque on said drum to produce substantially a condition of equilibrium permitting rotation of the drum in either direction through 360° or more with a minimum of effort including, a housing secured to the drum for movement therewith and having therein a power input shaft coaxial with the blade-mounting shaft, an idler shaft mounted in said housing for bodily movement therewith and having its axis eccentrically of the blade-mounting shaft axis, intermeshing gears and pinions carried by the input and idler shafts and by the blade-mounting shaft to establish a train of driving connections therebetween.
